CLAIM

The ornamental design for packaging with electronic device, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top front perspective view of packaging with electronic device showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the packaging with electronic device that form no part of the claimed design. In FIGS. 3, 6, and 7 the masked areas within the broken lines also show portions of the packaging with electronic device that form no part of the claimed design.
